UNITED STATES PATENT OFFICE.

JOHN M. DOWNER, OF TORONTO, ONTARIO, CANADA.

SANDPAPERING AND GRINDING MACHINE.

1,259,494.

Specification of Letters Patent.

Patented Mar. 19, 1918.

Application filed July 31, 1913, Serial No. 782,200. Renewed February 5, 1918. Serial No. 215,560.

To all whom it may concern:

Be it known that I, JOHN M. DOWNER, a subject of the King of Great Britain, and resident of the city of Toronto, county of York, Province of Ontario, in the Dominion of Canada, have invented certain new and useful Improvements in Sandpapering and Grinding Machines, described in the following specification and illustrated in the accompanying drawings, that form part of the same.

The principal objects of this invention are, to effect a saving of time and labor in wood or metal working shops thereby materially reducing the costs of production.

A further object is to provide a machine with which accurate and uniform work can be accomplished.

The principal feature of this invention consists in the novel construction and arrangement of parts whereby sand papering or grinding members are operatively arranged upon a supporting frame and adjustable tables are provided adjacent to said grinding members upon which the work to be ground or sand papered is supported.

In the drawings, Figure 1 is a perspective view of my improved machine a portion of the frame being broken away to disclose a portion of the interior mechanism.

Fig. 2 is a side elevational and part sectional view of the machine.

Fig. 3 is a detailed view showing the adjustable eccentric support for the means for reciprocating one of the grinders.

Like numerals of reference indicate corresponding parts in each figure.

Referring to the drawings, 1 is the main frame of the machine which is here shown in the form of a hollow pedestal rectangular shaped in cross section and tapering upwardly from the base 2, having the top end 3 thereof open.

4 are bracket members rigid with the frame 1 and extending laterally therefrom adjacent to the top and carrying the journal bearings 5 at the upper ends.

6 is a shaft journaled in the bearings 5 and having the grinder disks 7 secured to the outer ends thereof.

8 is a pulley secured to the shaft 6 between the bearings 5 around which the driving belt 9 extends.

10 is a flanged pulley secured to the shaft 6 centrally above the open top 3 of the main frame.

11 is an arm rigidly secured to the front side of the main frame adjacent to the bottom and projecting horizontally outward therefrom having the journal bearing 12 at the outer end.

13 is an arm rigidly secured to the front of the frame 1 adjacent to the top thereof, said arm extending horizontally outward and having a journal 14 at its outer end arranged in vertical alinement with the journal 12.

15 is a vertical spindle journaled in the bearings 12 and 14 extending thereabove and 16 is a small spindle secured to the top of the spindle 15 upon which is mounted a grinding cylinder 17 which may be of any desired diameter.

18 is a pulley secured to the spindle 15 a short distance above the journal 12.

19 is a shaft horizontally arranged within the main frame 1 having the ends secured in the sides of said frame intermediate of its height.

20 is a pulley rotatably arranged upon the shaft 18 between the sides of the frame.

21 is a bracket rigidly secured to the rear side of the frame and having a bracket 22 adjustably supported thereon in which is journaled a pulley 23.

24 is an endless belt which extends over the flanged pulley 10 on the shaft 6 and downwardly within the main frame and under the pulley 20 from whence it extends outwardly through an opening 25 in the front of said frame and around the pulley 17 on the vertical spindle 15. The belt having a quarter turn and extending around said pulley it passes rearwardly to the pulley 23 supported on the adjustable bracket. 95 From thence the belt returns outside of the frame 1 to the pulley 10. The belt 24 is kept in proper tension by adjusting the bracket 22.

26 is a rocker arm pivotally supported intermediate of its length on the bracket 27 at the rear side of the frame 1 to one side of said rocker arm having a horizontally arranged fork 28 at its outer end.

29 is a collar rotatably secured upon the spindle 15 a short distance above the bearing 12 and having a pair of laterally extending gudgeons 30 which are journaled in the bearings 31 on the outer end of the fork 28.

32 is a vertically arranged fork formed on the inner end of the rocker arm 26.

33 is a flanged sleeve secured in one of the

side walls of the main frame below the shaft 19.

34 is a stud fitted into the sleeve 33 and having a reduced threaded outer end 35 upon which is threaded a lock nut 36. The outer extremity of the stud 34 is formed with a square end 37.

38 is an eccentrically arranged portion of the stud 34 extending inwardly into the frame and upon which is journaled the spur gear wheel 39, said spur gear having a sleeve hub 40 carrying an eccentric 41 on its inner end adapted to extend into the fork 32 on the inner end of the rocker arm 26. The spur gear 39 is adapted to mesh with a spur pinion 42 secured to the pulley 20, but the said spur gear may be moved out of mesh with said pinion by rotating the stud 34 within the sleeve 33 swinging the eccentrically arranged end 38 downwardly.

43 and 44 are a pair of socket members preferably formed integral with the main frame 1 arranged on the sides thereof in perpendicular alignment and slightly to one side of the vertical center.

45 is a square bar rigidly secured in said socket members.

46 is a block slidably arranged on the bar 45 and split longitudinally on one corner 30 having the lugs 47 arranged intermediate of its length in which a suitable clamping member 48 is secured.

49 is a cylindrical socket member preferably formed integral with the block 46 and arranged horizontally and in parallel alignment with the shaft 6 and preferably in the same perpendicular plane. The socket member 49 is preferably formed with a horizontal cylindrical hole extending from end 40 to end thereof.

50 is a bar having a rounded end fitting in the socket 49 and held from turning by the set screws 51. The outer portion of the bar 50 is square.

52 is a square sleeve slidably arranged upon the squared end of the bar 50 and split longitudinally and formed with the lugs 53 adapted to be clamped together.

54 is an upright carried by the sleeve 52, said upright having secured at its upper end in a suitable guide-way a segmental member 54^a, said segmental member being adapted to be swung forward or backward and having an arc-shaped slot 55 therein through which extends the bolt of the clamping member 56. The lower edge of the segmental member is formed with worm gear teeth adapted to engage the worm 57 secured to the spindle 58 journaled in the lugs 59 extending from one side of the upright 54.

60 is a table secured to the segmental member 54^a and having its inner edge arranged close to the grinder disk 7. The table 60 may be adjusted to any desired angle by rotating the spindle 58 by means of

the hand wheel at the outer end thereof, said spindle operating the worm in the worm gear portion of the segment. The table may be held rigidly in any desired position by means of the clamp member 56. The table 70 may be adjusted close to the face of the grinder disk or away from the same by sliding the sleeve 52 carrying the upright upon the bar 50 and the height of the table may be regulated to any desired position by adjusting the position of the block 46 upon the vertical bar 45.

It will thus be seen that any arrangement or adjustment may be had. The construction herein described for the adjustable table 80 for the grinder disk is duplicated on each side of the machine.

61 is an arm secured to the front face of the frame immediately above the opening 25 and extending horizontally outward therefrom having a square socket 62 at the outer end.

63 is a square bar secured in the socket 62 and extending upwardly therefrom having the upper end firmly secured in the square 90 socket portion 64 of the arm 13 arranged immediately behind the journal bearing 14.

65 is a block slidably arranged on the bar 63 and split longitudinally and adapted to be clamped thereon to be held in any desired 95 position. Said block having a transversely arranged socket member 66 formed rigid therewith.

67 is a square bar secured in the socket 66 and extending horizontally outward therefrom past the spindle 15.

68 is a split sleeve slidably arranged on the outer end of the bar 67 and carrying the upright 69, which upright is identical in formation with the upright 54 except that it 105 is shorter in length.

70 is a table carried upon the upright 69 by a rocking mechanism precisely the same as that supporting the table 60, said table 70 having a circular opening 71 therethrough 110 through which the grinding cylinder 17 carried on the vertical spindle 15 extends.

The circle opening 71 is preferably formed with an inwardly projecting annular flange 115 72 at the bottom edge.

73 is a ring member formed with a flanged edge adapted to fit within the circle 71 and to rest upon the flange 72. This ring is made removable so that different sizes of rings may be used according to the size of 120 the grinder cylinder.

This arrangement of rings is provided so that different sizes of grinding cylinders may be used.

In the use of this device, it is set up in 125 the desired position in the shop and the pulley 8 is belted up to a suitable driving means. The rotation of the pulley 8 operates the shaft 6 and consequently the grinding disks 7 so that the mechanic desiring to 130

grind a flat surface may place his work on either of the tables 60 and after adjusting the tables to the desired angle and height may grind the surface desired. A perfectly 5 secure adjustable rest is provided for the work and very accurate surfacing may be accomplished whether a flat surface or a convexed curved surface is desired.

In the grinding of flat surfaces it may be 10 found desirable to use a pendulum movement and when this is desired the set screws 51 holding the bar 50 may be loosened when the standard may be rocked backward and forward on the pivot or if desired the whole 15 table may be removed and a special pendulum table inserted into the socket.

The rotation of the shaft 6 causes the 20 operation of the spindle 15 and shaft 18 through the endless belt 24 extending around the several pulleys in the manner described. On the rotation of the shaft 18 the spur 25 gear 39 meshing with the pinion 42 is rotated and the eccentric carried by the said spur gear operating in the fork end 32 of the rocker arm 36 rocks said arm upon its pivot thus imparting a reciprocal movement to the vertical spindle 15 through the connection to the forked end 28 of said rocker arm. The said spindle and grinding cylinder 30 carried thereby are thus reciprocated vertically consequently the cylinder will wear uniformly and will also insure a smooth and uniform surface being ground upon the piece of material held there.

The table 70 may be adjusted to any desired angle to facilitate the handling of the work and may be raised and lowered as desired.

A machine such as described is very compact, simple and effective in its operation allowing a great flexibility in use and where utilized in a woodworking establishment, particularly in pattern making where a great deal of shaping and surfacing is necessary, a great deal of time will be saved and much better work produced. The machine may also be used to great advantage in metal working.

Another important feature about this machine is, that the grinder cylinders used upon the vertical spindle are adapted to be used upon the horizontal shaft if desired, it being simply necessary to unscrew the spindle 16 and after removing the disk from the shaft 6 screwing the spindle 16 into the end of the said shaft. This interchangeable feature allows the use of the machine for flat surface grinding as the work may be placed upon a table and run under the horizontally arranged rotating cylinder.

A further feature of utility in this machine is the provision of a table 74 arranged between the disks so that the operator in grinding the work may grind on either the 65 right or left side without moving around

the machine utilizing the inner or back faces of the disks as these are double sided.

I have herein shown and described a machine equipped with horizontal and vertical grinders but it must be understood that I 70 may utilize the vertical grinding member separate from the horizontal grinders without departing from the spirit of the invention.

What I claim as my invention is:— 75

1. In a sand-papering and grinding machine, a pedestal frame, arms extending horizontally from said frame and supporting perpendicular journals, a spindle journaled perpendicularly in said journals, an 80 abrasive cylinder secured to said spindle, means for rotating said spindle, a rocker arm pivotally supported intermediate of its length on said pedestal and having its outer end operatively connected to said spindle to 85 reciprocate same, and an eccentric member arranged within said pedestal and operatively engaging the inner end of said rocker arm.

2. In a sand-papering and grinding machine, a frame, a spindle journaled perpendicularly in said frame, an abrasive cylinder secured to said spindle, means for rotating said spindle, a rocker arm pivotally supported intermediate of its length on said 90 frame and having its outer end operatively connected to said spindle to reciprocate same and having the inner end slotted, a stud secured in said frame, an eccentric journaled on said stud and extending into 95 the slotted end of said rocker arm, and means for rotating said eccentric.

3. In a sand-papering and grinding machine, the combination with a main frame and horizontally journaled grinder shaft, of 105 a spindle vertically journaled, a shaft arranged horizontally in said frame below said grinder shaft, a pulley on said intermediate shaft, a belt operating on said grinder shaft and extending around said pulley, a spur 110 pinion rotating with said pulley, a spur gear meshing with said spur pinion and suitably journaled from the frame, said spur gear having an eccentric connected thereto, a rocker arm pivotally supported intermediate 115 of its length from said frame and having one end engaging said eccentric and the other end operatively connected with the vertical spindle and adapted to reciprocate the same.

4. In a sand-papering and grinding machine, the combination with a main frame and horizontally journaled grinder shaft, of a vertical grinder spindle suitably journaled and rotated, a stud rotatably secured in said 125 frame and having an eccentric inner end, means for securing said stud from rotation, a gear wheel mounted on the eccentric end of said stud and operatively connected to rotate with the grinder shafts, said spur gear 130.

- having an eccentric end, a rocker arm having a forked end engaging the eccentric carried by said gear wheel and a forked outer end operatively connected with the vertical spindle and adapted to reciprocate said spindle.
5. In a sand-papering and grinding machine, the combination with a main frame and horizontally journaled grinder shaft, of a vertical grinder spindle suitably journaled 10 and rotated, a journal bearing arranged in the side of the frame, a stud rotatably arranged in said journal bearing and having an eccentrically arranged inner end and a threaded outer end having a square extremity, a nut threaded on the outer end of said stud and adapted to lock it securely from rotation, a spur gear rotatably supported on the eccentric end of said stud and having an eccentric inner end, a rocker arm operatively 15 connected with said eccentric and having its outer end operatively connected with said vertical spindle to reciprocate the same, and a spur pinion suitably journaled and rotated and adapted to mesh with said spur gear.
- 20 6. In a sand-papering and grinding machine, the combination with a main frame and spindle grinding member, a vertically arranged bar rigidly supported from said frame, a clamping member slidably and non-rotatably secured to said vertical member, a horizontally adjustable member connected to said vertically adjustable member, and a table adjustably supported upon the horizontal adjustable member.
- 25 7. In a sand-papering and grinding machine, the combination with a main frame and rotary grinding member, of a rigid vertical 30 guide bar, an arm slidably and non-rotatively supported on said bar, an upright slidably and non-rotatively supported on 40 said arm, and a table adjustably supported on said upright adjacent to said grinding member.
8. In a sand-papering and grinding machine, the combination with a main frame and rotary grinding member, of a vertically and horizontally adjustable upright arranged adjacent to said grinding member, a segmental member supported on said upright, said segmental member having an arc-shaped slot and a projecting flange formed with worm wheel teeth, a worm journaled on said upright and meshing with said toothed segment, said worm having an extension spindle and a hand wheel, a clamping member extending through said slot and adapted to lock said segments in various adjusted positions, and a table secured to said segment.
5. In a sand-papering and grinding machine, the combination with a main frame and a vertical grinder spindle, of a table adjustably supported from said frame and having a circular opening through which said spindle extends, said circular opening 50 having a flanged lower edge, and a removable ring adapted to fit into the opening in said table.
- Signed at the city of Toronto, Ontario, Canada, this 28th day of July 1913.
